DESIGN.

W. BERK.

AUTO TAIL LAMP.

APPLICATION FILED DEC. 16, 1919.

55,021.

Patented May 4, 1920.

William Berk,
Inventor

By his Attorney
Macdonald & Macdonald.

UNITED STATES PATENT OFFICE.

WILLIAM BERK, OF NEW YORK, N. Y., ASSIGNOR TO AMERICAN AUTO LAMP COMPANY, INC., OF NEW YORK, N. Y., A CORPORATION OF NEW YORK.

DESIGN FOR AN AUTO TAIL-LAMP.

55,021.

Specification for Design.

Patented May 4, 1920.

Application filed December 16, 1919. Serial No. 345,398. Term of patent 14 years.

To all whom it may concern:

Be it known that I, WILLIAM BERK, a citizen of the United States, residing in the borough of Manhattan, city, county, and State of New York, have invented a new, original, and ornamental Design for Auto Tail-Lamps, of which the following is a specification, reference being had to the accompanying drawing, forming part thereof.

The figure is a perspective view of an auto tail lamp, showing my new design.

I claim:

An ornamental design for an auto tail lamp, as shown.

WM. BERK.

In the presence of—

D. DAMVIT,
BENJ. PUTTERMAN.
